UNITED STATES PATENT OFFICE

2,490,288

PROJECTOR FOR BOWLING BALLS

Frederick O. Wickersham, Chicago, Ill.

Application February 28, 1947, Serial No. 731,569

1 Claim. (Cl. 273—38)

1

The invention relates to table-type bowling apparatus.

One object of the invention is to provide a bowling apparatus which provides for improved directional control of the ball from a position from which it will gravitate down a chute to the runway, by the exercise of skill.

Other objects of the invention will appear from the detailed description.

The invention consists in the several novel features hereinafter set forth, and more particularly defined by the claim at the conclusion hereof.

In the drawings:

Fig. 1 is a perspective of an apparatus embodying the invention.

Fig. 2 is a vertical longitudinal section through the chute, from which the ball is discharged.

Fig. 3 is a transverse section taken on line 3—3 of Fig. 2.

The invention is exemplified in a top panel, which forms the runway 10 over which the balls 26 are rolled. End supports 11 and 12 on the runway, are adapted to rest on a table. The panel which forms the runway 10, is provided with gutters 13 into which the balls roll when they are not discharged from the chute in the proper direction to strike bowling pins set on the spots 14. A hopper 15, surrounded by a guard 16 in the rear of the spots 14, is adapted to receive the balls after striking the bowling pins, and to discharge them through an opening 17 to a return trough 18 under the runway 10. Trough 18 is open at the front end of the runway for returning the balls to the player.

A chute 20 has an upper inclined face and a bottom overlying the top surface of the runway 10 and is pivotally mounted to swing horizontally over the front end portion of said runway. The upper face of chute 20 is provided with a groove 24 which is curved in cross-section for directionally controlling the gravitation of the ball down the chute. A shoulder 25 for retaining the ball in groove 24, is provided at the upper end of the chute and the lower end of groove 24 terminates so it is flush with the top of runway 10. From shoulder 25, the groove is longitudinally inclined so that the ball unless restrained, will gravitate and roll from the upper end of the chute down the groove 24 onto the runway 10, acquiring sufficient momentum to knock down the pins set up on the rear end of the runway.

A stop-pin 21 extending vertically through a bore in chute 20, has its lower end pivotally and slidably held in the runway 10 and end support 11. The pin 21 intersects the center of groove

2

24 at its upper end and when the pin is raised, projects in front of the ball 26, to restrain it from gravitating down the groove 24, as illustrated in Fig. 2. When the stop-pin 21 is depressed below the groove 24, the ball will be released for gravitation and roll down the chute.

A pin 30 extends transversely through pin 21 and a vertical slot 31 in chute 20 and its ends project from both sides of the chute to function as handles for vertically depressing the stop-pin 21 and for imparting horizontal pivotal movement to chute 20 and pin 21. A spring 28, the lower end of which is confined in socket 29 in support 11 and which has its upper end engaging an abutment 27 on pin 21, urges stop-pin 21 upwardly and permits it to be depressed for the withdrawal of its upper end from the path of ball 26 for releasing the ball for gravitation down the chute. The projector end of the runway is mounted so as to provide clearance for the downward movement of the stop-pin 21.

In operation, a ball 26 is placed in the upper end of groove 24 in front of shoulder 25 and will be held there by gravity against the front side of stop-pin 21. The player will then, by means of cross-pin 30, swing the stop-pin 21 horizontally and with it the chute 20, to angularly and directionally position the groove 24, for the directional control of the ball 26 toward the bowling-pins. In this setting, the upper end of the pin 21 and the vertical axis of the ball, may be used to aid in setting the chute into the angular position desired according to the skill of the player. Next, the player will depress both ends of cross-pin 30 to slide stop-pin 21 downwardly to clear the groove 24 and release ball 26 so it will gravitate and roll down the chute in the groove 24 toward the bowling-pins. When ball 26 has cleared the groove 24 in chute 20, the player will release cross-pin 30 and spring 28 will return stop-pin 21 to its raised position, in readiness for another play with the ball. The ball will be returned to the player through opening 17 and return runway 18.

The invention exemplifies bowling apparatus with a chute from which the ball is released for gravitation and rolling down a direction controlling groove to the runway by a stop-pin which intersects the groove, after the chute has been angularly set for directional control of the ball. This discharges the ball without a striking impulse, and enables the player to more skilfully control the direction of the ball toward the pins. The stop-pin rotates with the chute and its upper end is in alignment with the vertical axis of the

ball for aiding the player in directionally finding the desired angular setting of the chute.

The invention is not to be understood as limited to the details described, since these may be modified within the scope of the appended claim without departing from the spirit and scope of the invention.

Having thus described the invention, what I claim as new and desire to secure by Letters Patent is:

A projector for a bowling ball over a runway at one end of which bowling-pins are set, comprising: a chute overlying and having its bottom engaging the upper face of the front end of the runway and provided with an inclined groove in its front face for directionally guiding the ball as it gravitates to the runway, a stop-pin extending vertically through and slidably in the chute and runway, and pivoted in the runway, the upper end of the stop-pin being adapted to retain a

4
ball against rolling down the chute by gravity, spring-means under the runway for urging the stop-pin into ball-retaining position, the chute being provided with a slot in its sides, and a cross-pin on the stop-pin, extending through said slot and projecting from the chute, for depressing the pin to release the ball for gravitation down the groove and connecting the runway to the stop-pin so the chute may be pivotally shifted by the cross-pin.
